UNITED STATES PATENT OFFICE.

HARRY D. LILLIBRIDGE, OF ZANESVILLE, OHIO, ASSIGNOR TO AMERICAN ENCAUSTIC
TILING COMPANY, LTD., OF NEW YORK, N. Y., A CORPORATION OF NEW YORK.

DISCHARGE LOADING MEANS FOR TILE-CLEANING MACHINES.

Original application filed July 27, 1921, Serial No. 487,854. Divided and this application filed April 16, 1925. Serial No. 23,594.

This invention is a loading means for a tile cleaning machine whereby cleaned tiles are delivered automatically into receptacles in a manner to minimize breaking or chipping of the fragile material.

In a prior application Serial No. 487,854, of which the present application is one of a number of divisions, there is disclosed an organized machine embodying a plurality of mechanisms operating successively for receiving tiles, transporting tiles, agitating tiles by a tumbling action, and delivering cleaned tiles, and wherein the fragile tile material is handled by such successively acting mechanisms under conditions which, while effective in eliminating the sand adhering to the tile material, at the same time avoids to a marked extent the breaking of the tiles or chipping the edges thereof.

The present invention embodies means for effecting the delivery of the tile material from the tumbling screen cylinder to a receptacle positioned at the off-take end of the machine, and the objects are, first, to load the cleaned tile product into the receptacle in a way to avoid breaking the tiles or chipping the edges thereof, and, second, to dispense with hand labor in such delivery.

According to my invention, the loading mechanism embodies a movable carrier positioned for receiving the product from the treating mechanism, said carrier being depressible under the weight of the load as it accumulates within a receptacle adapted to be supported by the carrier, whereby the receptacle is maintained normally in a determined relation to the treating mechanism to minimize the distance to be traveled by the product on its way from the treating mechanism into said receptacle.

In a preferred form, the depressible load-carrier is pivoted for movement with respect to the treating mechanism, and is counterpoised so as to maintain said carrier at the required minimum distance from said treating mechanism. Co-operating with said carrier is a latch or detent adapted for locking the carrier in a lowered position, whereby a loaded receptacle may be shifted from the carrier to a roller bed or conveyor and thus a filled receptacle may be replaced by an empty receptacle.

It is desirable to employ a conveyor be-

tween the load-receiving carrier and the tumbling screen cylinder, the latter constituting the treating mechanism. The cleaned product from said cylinder is deposited upon the conveyor and thus preliminarily spread out for delivery into the receptacle of the depressible carrier.

Other functions and advantages of the invention will appear from the following description taken in connection with the drawings, wherein—

Figure 1 is a side elevation of a tile cleaning machine which includes a depressible load-discharge mechanism of my invention.

Figure 2 is a plan view with the screen cylinder of the treating mechanism omitted.

Figure 3 is an end view illustrating the rear of the machine. Figure 4 is an enlarged side view, partly in section, showing the load-discharging means in a normal operative relation to the treating means.

Figure 5 is a vertical cross section on the line 5—5 of Figure 4.

The organized machine for cleaning tiles includes a feed hopper A, an inclined runway B, an elevator or conveyor C, a treating mechanism shown as a tile tumbling screen cylinder D, and the novel load-discharging mechanism which latter constitutes the subject-matter of the present application.

As shown, the screen cylinder is provided with external bands d' resting upon grooved rolls i provided on a plurality of longitudinal shafts F F, the latter extending lengthwise of a frame member a² and inclined with reference thereto for supporting the treating cylinder D in an inclined position. The treating cylinder is open at the lower end for the free exit of the tile product adapted to be tumbled within the cylinder by the rotative movement thereof. For imparting rotative motion to the treating cylinder, the shafts F F are rotated through bevel gears h from a cross shaft E having a belt pulley E', and this cross shaft E is geared at g' to another cross shaft g which latter is provided with a friction roller or pulley e' adapted to drive the endless elevator or conveyor C, the latter operating to carry the product from hopper A and to deposit the same within the receiving end of the treating cylinder D.

J is the depressible carrier for receiving the load discharged from the treating mech-

anism D. This carrier is shown as a platform provided with a series of rollers J' suitably journaled on the platform to extend crosswise thereof. The carrier is provided, also, with a plurality of arms m, m, which are made fast with a horizontal rock shaft m' that is journaled in bearings provided by brackets m² which are fixedly attached to the rear part of the frame member a². Said carrier is supported in a movable relation to the treating mechanism D and to a roller bed N, and to normally maintain said carrier in a loading relation to said treating means D the carrier is counterpoised, for which purpose the rock shaft m' is provided with an arm m³, to which arm is pivoted a rod m⁴ which is equipped with a weight K, the ponderosity of which is sufficient to lift the carrier J and a receptacle into close relation to the discharge of the treating mechanism and which weight is overcome gradually by the accumulation of the load within said receptacle so that the carrier is depressed ultimately into an alined position relative to the roller bed N.

As shown, the roller table is a framework or bed n² with a series of idle rolls n' extending crosswise of the path of material passing through the treating machine, said roller table being at a height convenient to the attendant in placing an empty receptacle upon the roller bed and in removing filled receptacles from the same. Intermediate its ends, the frame or bed n² of the roller table is provided with a recess n into which the depressible carrier J is adapted to move under the weight of the load accumulated in the receptacle, indicated by the dotted line at L in Figure 4. When thus lowered, the depressible carrier J is in a flush relation to the roller bed N and the rollers J' of said carrier are in the plane, substantially, of the rollers n' of the bed, see full lines in Figure 3, whereby a filled or loaded receptacle L on the carrier may be slid off the rolls J' of the carrier onto the rolls n' of the bed, and in like manner an empty receptacle on the roller bed N may be shifted from said bed onto the rollers of the depressible carrier.

For locking the carrier with a loaded receptacle in the lowermost position, I provide a latch or detent o, extending vertically at one side of the carrier and adapted for locking engagement therewith. This latch or detent is pivoted at its lower end to a release lever or treadle O, hung at o² intermediate its ends on the lower part of the frame member a², and the inner end of which lever is counterpoised by weight o', see Figure 4. A downward movement of the free end of lever or treadle O withdraws the latch or detent o from engagement with the carrier, J, whereupon the counterpoise K swings the carrier, and an empty recep-

tacle on said carrier, in an upward direction and thus restores the carrier to the desired normal operative relation to the discharge of the treating mechanism.

As illustrated, the loading carrier is at a distance from the delivery end of the treating cylinder D, and to bridge the space between J and D, there is provided a chute H and an endless conveyor I, although these elements H I may be dispensed with by coordinating the carrier J in operative relation to the cylinder D for loading the product from one to the other directly.

The chute H is supported in a fixed position within the frame member a² and is inclined slightly from the screen cylinder D to an overhanging relation to the depressible carrier J and its receptacle L. As shown, the chute is provided with raised sides and a raised loading end, but the bottom H' of said chute is perforated at h⁵, in Figure 5, for the free exit of sand which, with the cleaned tile product, is discharged from the open end of the inclined screen cylinder D.

The conveyor I is shown in operative relation to the chute, for the upper lead or run of said conveyor to traverse the perforated bottom H' of said chute. The length of the conveyor exceeds the length of the chute, and said conveyor is supported by rollers or pulleys j j', positioned beyond the respective end portions of said chute, see Figure 4. The roller j' is an idler on a shaft journaled in a bracket j' of the frame member a², whereas the roller j constitutes means for driving the conveyor because said roller j is fast with a cross shaft k, journaled in bearings of the frame member a², and which cross shaft k is operated by bevel gears k' from a countershaft k² which in turn is driven by sprocket gearing k³ from one of the two longitudinal shafts F. Provision is thus made for imparting traveling motion to the conveyor I adapted for carrying the material discharged from the treating cylinder D into the receptacle L on the depressible carrier J.

The operation will be apparent from the foregoing description, but may be recited briefly as follows:—Saggers loaded with burned tiles and sand are carried from a kiln and dumped into the hopper A, whereupon the conveyor or elevator C carries the tiles and sand from said hopper and deposits the same within the screen D. The rotary motion of the inclined screen imparts a tumbling and feeding action to the material, whereby the tiles are frictionally rubbed to free them from the sand adhering to the surfaces thereof. The sand makes its exit from the cylinder D and some of it escapes from the conveyor C, but the tiles in a cleaned condition are delivered from the rear open end of the cylinder upon the conveyor I which with the chute deposits the

tiles into the receptacle L on the depressible carrier J, the same being in a close normal relation to the delivery end portions of the conveyor I and the chute H. As the tiles 5 cumulate within the receptacle L, the increase in the weight of the load depresses the pivoted carrier J and lifts the counterpoise K, and this depression of the carrier is continued during the deposit of the material 10 within the receptacle until said carrier moves downwardly into the horizontal plane of the roller bed, thereby alining the rollers J' of the carrier with the rollers n' of the roller bed. At this stage, the carrier J occupies 15 the recess n of the roller bed, and thus the latch o is brought into locking engagement with the carrier, the effect of which is to retain the carrier against movement. The attendant is now in a position to slide the 20 loaded receptacle L from the carrier to the roller table on one side or the other of such table, the rollers facilitating the movement of the loaded receptacle, and thereafter an empty receptacle is positioned upon the 25 carrier, and the latch is released, so that the counterpoise will act to swing the carrier upwardly and present the empty receptacle into loading relation to the chute and the conveyor. 30 In the loading mechanism of my invention the carrier supports a receptacle in a position close to the conveyor, and this carrier is depressed gradually by the accumulation within the receptacle, whereby the 35 slowly descending carrier minimizes the distance through which the tiles descend from the conveyor until they lodge upon the pile growing within the receptacle, thus reducing to a minimum the liability of breaking 40 the tiles or of chipping the edges thereof.

Having thus fully described the invention, what I claim as new and desire to secure by Letters Patent is:

1. In a tile cleaning machine, a delivery 45 mechanism for cleaned tiles embodying a delivery conveyor positioned in loading relation to tile-cleaning means, whereby tiles from said cleaning means are deposited upon said delivery conveyor and are free to spread over the surface of said conveyor, a pivoted 50 carrier hung below the delivery end of said conveyor for movement relatively to said conveyor, said carrier having a roller bed for supporting a separate receptacle in loading 55 relation to the delivery conveyor, means for balancing said pivoted carrier and the load imposed progressively thereon by the action of the delivery conveyor in feeding cleaned tiles to the receptacle, and offbearing 60 ing conveying means positioned for receiv-

ing the loaded receptacle upon the depression of the pivoted carrier to substantially the plane of said offbearing conveying means.

2. In a tile cleaning machine, a delivery 65 mechanism for cleaned tiles embodying a delivery conveyor positioned in loading relation to tile-cleaning means whereby tiles from said cleaning means are tumbled upon the delivery conveyor and are free to spread 70 over the surface of said conveyor, a chute with a perforated bottom over which the delivery conveyor is movable in effecting a separation of sand from cleaned tiles, a pivoted carrier having a roller bed for receiving and supporting a separate receptacle into which the cleaned tiles are deposited by the action of said delivery conveyor, said pivoted carrier being hung for movement 75 relatively to the delivery end of said conveyor, means for balancing the weight of the pivoted carrier and of the load imposed progressively thereon by the action of the delivery conveyor in feeding tiles to the receptacle adapted to be placed upon the pivoted carrier, and offbearing conveying means 80 extending transversely to the line of material fed by the delivery conveyor, said offbearing means being positioned for receiving the receptacle on said pivoted carrier when the latter is depressed by the accumulated load within said receptacle. 85

3. In a tile cleaning machine, a delivery 90 mechanism for cleaned tiles embodying a delivery conveyor positioned in loading relation to tile-cleaning means whereby tiles from said cleaning means are deposited upon the delivery conveyor and are free to spread over the surface thereof, a pivoted 95 carrier hung below the discharge end of said delivery conveyor, said pivoted carrier being provided with means for receiving and supporting a receptacle into which cleaned tiles are accumulated by the feeding action of said delivery conveyor, a roller bed having a recess positioned for receiving said pivoted carrier, whereby the receptacle on said pivoted carrier is alined substantially with said roller bed, and means for locking and releasing the pivoted carrier 100 upon the depression of said carrier to occupy said recess whereby the carrier is retained in a locked relation to the roller bed for facilitating the removal of a loaded receptacle by sliding the latter off the carrier 110 and upon the roller bed. 115

In testimony whereof I have hereto signed my name this 13th day of April, 1925.

HARRY D. LILLIBRIDGE.
